UNITED STATES PATENT OFFICE.

MARTIN BEHRER, OF QUEENS, NEW YORK.

VALVE FOR FLUSH-TANKS.

1,209,662.

Specification of Letters Patent. Patented Dec. 26, 1916.

Application filed March 15, 1912. Serial No. 683,964.

To all whom it may concern:

Be it known that I, MARTIN BEHRER, a citizen of the United States, residing at Queens, in the borough of Queens, city of New York, county of Queens, and State of New York, have invented certain new and useful Improvements in Valves for Flush-Tanks, of which the following is a specification, reference being had therein to the accompanying drawings, which form a part thereof.

My invention relates to valves for flush tanks, and more particularly to a type of valve for use in siphon tanks. A tank of this character should possess the characteristics of being so constructed as to prevent any electrolytic action from interfering with the operation of the tank and thus be adapted for use in various localities wherein the character of the water differs; of being readily installed or repaired; and of operating in a manner which will prevent the accidental displacement of the jet valve through the ordinary actuation of the chain pull.

With these conditions in mind, the main object of the invention is to provide a valve of this character wherein a weighted valve block is used to control the jet for initiating the actuation of the siphon, which valve block will have lineal movement toward and from its seat, the valve in its movement being guided and controlled in a manner to insure the proper seating of the block while at the same time preventing the displacement of the block through any excessive movement thereof due to momentum acquired through excessive stresses upon the pull chain.

A further object is to provide a guide mechanism which will permit the valve block to be lifted from its seat and removed from the tank at any time without a necessity for the employment of any tools or the removal of any parts other than the valve block itself.

A still further object is to provide a valve of this character wherein any corrosion due to the character of the water used in the tank will not interfere with the free movement, and accurate seating, of the valve block.

A still further object is to provide a valve mechanism wherein in case of leakage at the jet valve, due to wear of the packing, the packing may be quickly removed and replaced by new packing, without the aid of tools or machinery of any kind.

A still further object is to provide a valve wherein the packing of the valve block will be so constructed and arranged as to permit the accurate seating of the valve irrespective of irregularities in the valve seat, and wherein the arrangement of this packing will be such as to cause the weight of the water in the tank to aid in the seating of the valve block.

A still further object is to provide an interchangeable valve block packing of the character immediately above referred to wherein the weight of the water, or the resistance to the movement of the valve block, will not displace the said packing. And a still further object is to simplify the structure of the valve in a manner to minimize likelihood of a loss of adjustment, or injury thereto under the ordinary conditions of use.

The invention consists primarily in a valve for flush tanks, embodying therein a siphon tube, a flush pipe normally in communication therewith, a siphon jet lead discharging into said flush pipe below said siphon tube and across the outlet thereof, an elongated guide rod projecting axially of said siphon jet lead, a weighted valve block slidably mounted upon said guide rod, an elongated stem carried by said block and inclosing said rod, and means in conjunction with said stem for raising said valve block; and in such other novel features of construction and combination of parts as are herein-after set forth and described, and more particularly pointed out in the claims hereto appended.

Referring to the drawings: Figure 1 is a sectional elevation of a flush tank embodying my valve mechanism; and Fig. 2 is an enlarged vertical section of the valve mechanism alone.

Like letters refer to like parts in both of said views.

In the embodiment of my invention shown in the drawings, *a* indicates an ordinary flush tank which is provided with an ordinary float inlet valve control mechanism and overflow pipe, not shown, and with a pull cord mechanism *b*.

Mounted in the tank *a* is a siphon tube, one leg *c* of which opens into the tank and the other leg *d* of which is mounted in one lead *e'* of a three way casting *e*, another lead *e''* of which casting is in communication with the flush pipe *f*. The siphon tube thus normally communicates with the flush pipe

f, the passage through the casting *e* being unobstructed. A suitable packing *g* is provided about the lead *e*² of the casting *e* and the bottom of the flush tank.

5 The casting *e* has a siphon jet lead *e*³ extending at a curve from adjacent to the bottom of the tank *a* to a point above the lead *e*², and across the lead *e'*, thus permitting the water admitted through the lead *e*³ to be 10 projected across the lead *e'* and into the flush pipe *f*.

The upper face of the lead *e*³ has a valve seat *h* formed within its inlet, and permanently secured to the casting *e* is a vertical 15 guide rod *i* projecting axially of the lead *e*³ and extending upwardly to a height above the greatest possible displacement of the valve mechanism under the control of the pull chain mechanism *b*.

20 Slidably mounted upon the guide rod *i* is a weighted valve block *k*, which has permanently secured thereto a tubular stem *m*, the bore of which is of a diameter slightly larger than that of the rod *i* to afford play 25 between these parts for the purpose of permitting that slight lateral movement of the valve block *k* desirable to secure the proper seating thereof under all conditions of use.

The pull cord mechanism *b* is attached to 30 the stem *m* by means of the opening *m'* therein, the free end of said stem being closed in the manner shown in the drawings to prevent the percolation of any water through this tube and the consequent accidental initiation of the siphon action to 35 discharge the water in the tank.

Adjacent to the lower face of the valve block *k* said block is channeled out to form oppositely disposed shoulders *k'* and *k*² and 40 seated in this channel is a detachable rubber packing ring *n* having a reduced portion *n'* adjacent to the shoulder *k'* and an enlarged portion *n*² adjacent to the shoulder *k*², this portion being beveled at *n*³ as shown to 45 conform to the valve seat *h* and afford a flexible edge adapted to be forced, by the weight of the water within the tank, into the desired intimate engagement with said seat. The arrangement of the shoulders *k'* and 50 *k*² is such as to prevent the displacement of this packing rim through the resistance encountered thereby when the valve is raised, and the flexibility of this ring in connection with the enlarged bore of the stem *m* permits 55 the valve to automatically find a seat even though the seat itself be slightly irregular or if there be a slight obstruction thereon. This packing ring also makes the operation of the device noiseless.

60 By making the valve stem *m* of solid stock drilled, leakage at the top of the stem is positively prevented without the aid of packing of any kind which might deteriorate from continued use or be displaced 65 through the stresses upon the stem, thus

avoiding possibility of the development of leaks through this stem from continuous use.

The operation of the herein described valve is substantially as follows:—When it 70 is desired to flush a closet, it is merely necessary to give the chain pull *b* one pull, this movement serving to raise the valve block *k*, through its stem *m*, from its seat *h*. As the block is thus raised, water from the tank 75 will flow through the lead *e*³, through the constricted opening adjacent to the flush pipe *f* and across the discharge end of the lead *e'*, developing a partial vacuum sufficient 80 to start the siphon action in the siphon tube in the usual and well known manner. As the pull chain is released, the weight of the block *k* will cause it to seat by gravity, the water about the lead *e'* and within the hollow stem *m* affording sufficient resistance 85 to the descent of said block to insure an easy seating thereof. The resistance within the stem *m* is merely incidental to the use of the apparatus. As the valve *k* rises and falls, its movement is guided by the rod *i* which occupies a fixed position in relation to the inlet of the lead *e*³ and thus limits the movement of the block in a manner to insure its proper reseating as it descends through 90 gravity. This guide rod being elongated and seated within the stem *m*, sufficient movement of the valve block *k*, under the chain pull, to permit it to escape from said 95 guide rod is prevented through the extended bearing between it and the stem *m*.

The packing ring *n* being of flexible rubber, will conform to the valve seat *h* under the weight of the valve block, although if any obstructions should rest upon said seat or any irregularities be developed therein, the flexible edge of said ring would be forced to seat by the weight of the water in the tank. Furthermore, the bevel of the edge of this ring will tend to displace any 100 solid particles which may rest upon said seat.

In case repairs in the valve are required, it is merely necessary for the plumber to reach into the tank *a*, take hold of the stem *m* and remove the entire valve from the 115 guide rod *i*, slip the packing ring *n* from the channel between the shoulders *k'* and *k*² and substitute a new ring therefor. To replace the valve it is merely necessary to insert the guide rod *i* in the bearing of the 120 valve and its stem, and permit said block to drop into place. It will be observed that there are no obstructions which would prevent the free removal of this valve, and that repairs may be effected without the use 125 of tools of any kind. This feature is very important as where it is necessary to remove a part of the valve mechanism which is attached by means of screws, the corrosion which occurs upon the screws and about the 130

parts carrying same is so great that after continued use it is sometimes impossible to start the screws. Furthermore, the plumber is working at a disadvantage; often in 5 an awkward position with little room, so that the handling of tools is rendered difficult, and as a consequence, when repairs are needed it is necessary to take down the entire tank in order to give the mechanic an 10 opportunity to work freely upon the valve.

The channel between the shoulders k' and k^2 is of a depth sufficient to afford enough holding surface for the ring n to prevent the displacement thereof through 15 the resistance of the water within the tank, the flexible edge of said ring yielding to this resistance before sufficient power can be developed to remove the ring. Furthermore, the overhung top of the valve block k minimizes the resistance to the movement of 20 this ring.

In the construction herein described, I have reduced the number of parts incorporated in the mechanism to a minimum, and 25 these parts are so associated as to preclude their disarrangement through the ordinary conditions of use.

It is not my intention to limit the invention to the precise details of construction 30 shown in the accompanying drawings, it being apparent that such may be varied without departing from the spirit and scope of the invention.

Having described my invention, what I 35 claim as new and desire to have protected by Letters Patent, is:—

1. A valve for flush tanks, embodying therein a siphon tube, a flush pipe normally in communication therewith, a siphon 40 jet lead discharging into said flush pipe below said siphon tube and across the outlet thereof, said lead having a seat about the inlet thereof, the space above said siphon jet lead and about said seat being entirely un- 45 obstructed, an elongated guide rod secured at the bottom of and projecting axially of said siphon jet lead, a weighted valve block slidably mounted upon said guide rod, an elongated stem carried by said block and 50 inclosing said rod, and means in conjunction with said stem for raising said valve block.

2. A valve for flush tanks embodying therein a siphon tube, a flush pipe normally in communication therewith, a siphon 55 jet lead discharging into said flush pipe below said siphon tube and across the outlet thereof, said lead having a seat about the inlet thereof, the space above said siphon 60 jet lead and about said seat being entirely

unobstructed, an elongated guide rod secured at the bottom of and projecting axially of said siphon jet lead, a weighted valve block slidably mounted upon said guide rod, a detachable packing ring 65 carried by said block and adapted to engage the seat about said siphon jet lead, an elongated stem carried by said block and inclosing said rod, and means in conjunction with said stem for raising said valve block. 70

3. A valve for flush tanks, embodying therein a siphon tube, a three-way fitting, one lead of which is in communication with said tube, a flush pipe in communication with another lead of said fitting, an elongated guide rod secured at the bottom of and projecting axially of the third lead of 75 said fitting, the inlet of said lead being unobstructed above and about the edge thereof, a weighted valve block slidably mounted upon said guide rod, an elongated stem carried by said block and inclosing said rod, and means in conjunction with said stem for raising said valve block, whereby water may be admitted to said fitting in a 80 manner to cause it to flow across the lead thereof communicating with said siphon tube and to discharge into said lead in communication with said flush pipe. 85

4. A valve for flush tanks embodying 90 therein a siphon tube, a flush pipe normally in communication therewith, a siphon jet lead discharging into said flush pipe below said siphon tube and across the outlet thereof, said lead having a seat formed 95 about the inlet thereof, the space above said siphon jet lead and about said seat being entirely unobstructed, an elongated guide rod secured at the bottom of and projecting axially of said siphon lead, a weighted valve 100 block slidably mounted upon said guide rod, said block having a channel in the sides thereof forming oppositely disposed shoulders, and a detachable annular packing seated in said channel, and having an 105 overhung rim, an elongated stem carried by said block and having a loose sliding fit with said rod whereby slight movement of said block is afforded to permit said packing to automatically seat itself, and means 110 in conjunction with said stem for raising said block.

In witness whereof, I have hereunto affixed my signature, in the presence of two subscribing witnesses, this 5 day of March, 115 1912.

MARTIN BEHRER.
